PNEUMATIC PLAYER MECHANISM.

1,168,924.

Specification of Letters Patent. Patented Jan. 18, 1916.

Application filed April 2, 1915. Serial No. 18,687.

To all whom it may concern:

Be it known that I, FRANK C. WHITE, a citizen of the United States, residing at Meriden, New Haven county, State of Connecticut, have invented certain new and useful Improvements in Pneumatic Player Mechanism, of which the following is a full, clear, and exact description.

My invention relates to music player mechanism and is particularly useful in connection with pneumatic piano playing apparatus, designed to be actuated either by a power-driven exhauster, or a manually operated exhauster, or both. In the first case, the instrument may be said to be operating automatically. In the second case, when power is being furnished by the foot-impelled exhauster, the instrument is being operated and controlled manually. In the third case, that is to say when the instrument is being driven normally by the power-driven exhauster and is therefore operating automatically, the player or operator may desire to vary the air tension from that which would be otherwise automatically effected, and my improvement aims to make it possible for him to effectively do so. For example, suppose a so-called "crash" effect is desired at any moment: The operator of the instrument may press the foot pedal powerfully so as to create the desired degree of high tension in the foot-impelled exhauster. This tension will be instantly transmitted to the action-chest to secure said "crash" effect, even though the power-driven exhauster is operating simultaneously therewith.

In the accompanying drawing I have illustrated my invention by a single conventional view, partly in section.

In said drawing, 1 conventionally represents an action-chest associated with the usual striker pneumatics, not shown.

2 represents conventionally the manually operated exhauster which may have the usual foot treadles, one being indicated at 3.

4 conventionally represents a power-driven exhauster which may be associated with any suitable form of motor 4^a by which it is driven.

5 represents a valve casing.

6 represents a duct leading from the exhauster 2 into chamber 7 of the valve casing.

8 is a port in one wall of chamber 7 leading into chamber 9 of said valve casing.

Chamber 9 is in communication with the action-chest 1 through duct 10.

11 is a duct leading from the power-driven exhauster 4 into chamber 12 of the casing 5.

14 is a port in one wall of chamber 12 which leads into the aforesaid chamber 9.

15 is a suitable valve for the port 8 which is self-closing in a direction to prevent air from passing through port 8 from chamber 7 into chamber 9.

16 is a similar valve for port 14, self-closing to prevent air from flowing from chamber 12 into chamber 9.

17 is a valve, preferably a slide valve, by which the port 14 may be more or less cut off at certain times, but which valve 17 normally stands open, as shown in solid lines in the drawing.

18 is a normally expanded pneumatic 75 suitably connected to valve 17.

19 is a port leading from the chamber 7 into the pneumatic 18.

20 is what I may term a leak opening in the duct 11, while 21 is a valve by which 80 this leak opening 20 may be wholly closed or opened to any desired degree, and by which the air tension on the power-driven side of the action may be varied even though the motor 4^a and the exhauster 4 are 85 working at a certain fixed speed.

It should be understood that the various parts which I have described may be modified in a variety of ways and that the drawing is merely a conventional illustration of 90 mechanism designed to perform a certain novel function in player apparatus of the character described.

Now as to the operation: Assuming the vacuum or air tension in the action-chest 95 is being produced by the exhauster 4, the parts will stand in the position shown in the solid lines in the drawing, the valve 16 being open and the valve 15 being closed. Should it at such a time be desired to manually increase the tension momentarily for any purpose, the operator may press powerfully upon the treadle 3 so as to secure the desired tension in the chamber 7. This should result in the quick opening of the 100 valve 15, but since it is necessary to first choke the port 14, and thereby the exhauster 4, before the exhauster 2 can overbalance the tension in the action being created by said exhauster 4, I provide choker 105 110

means for said port. To accomplish this result, in the preferred form, I provide the valve 17 which, when the air tension in the chamber 7 is suddenly increased, is closed more or less by the pneumatic 18, the latter being in communication with the chamber 7. When the valve 17 has sufficiently closed the port 14, and this is performed almost instantaneously, it is obvious that the effective tension of the power driven exhauster on the action will be instantly weakened and hence the valve 15 will readily open, so that the high tension manually effected by the pressing of the treadle 3 will be communicated quickly to the action. The degree to which the valve 17 closes the port 14 obviously varies according to the pressure on the foot treadle 3, and also according to the air tension in the chamber 12 and duct 11, all of which tensions are variable, because it is possible to manually press the treadle 3 with any desired degree of force, and because it is customary to provide means at the power-driven side of the action-chest 25 to vary the effective tension at that side when the instrument is being automatically played. While the valve 17 may fully close the port 14, in practice it would probably never have to fully close said port in the 30 performance of its function.

It will be understood that vacuum in the action may be secured wholly by the manually driven exhauster 2, in which event if the power driven exhauster 4 is not operating, the valve 16 will be closed, as indicated in dotted lines and the valve 15 will stand open, as also indicated in dotted lines. In this instance, the valve 16 prevents the exhauster 2 from drawing air from the 40 power exhauster side of the apparatus precisely as the valve 15 prevents the power driven exhauster from drawing air from the manually driven exhauster side of the apparatus when the latter is idle.

45 What I claim is:

1. In a pneumatic player apparatus, an action, a power driven exhauster in communication therewith, a manually driven exhauster, also in communication therewith, means operating to prevent the power driven exhauster from drawing air from the manually driven exhauster side, and means to prevent the manually driven exhauster from drawing air from the apparatus on the 55 power driven exhauster side, and means for automatically choking off the power exhauster upon the operation of the manual exhauster.

2. In a pneumatic player apparatus, an 60 action, a power driven exhauster in communication therewith, a manually driven exhauster also in communication therewith and partially through a common passage, check valves between said common passage and 65 each of said exhausters, said valves opening

toward said exhausters respectively whereby the exhausting of air from said common passage by one exhauster will tend to close the check valve for the other exhauster, and means for automatically choking off the power exhauster upon the operation of the manual exhauster operable by the air tension created by the operation of the manually driven exhauster.

3. In a pneumatic player apparatus, an 75 action, a power driven exhauster in communication therewith, a manually driven exhauster also in communication therewith and partially through a passage in common to both exhausters, check valves between said common passage and each of said exhausters, said valves opening toward said exhausters respectively whereby the exhausting of air from said common passage by one exhauster will tend to close the check valve for the 85 other exhauster, and means for automatically choking off the power exhauster upon the operation of the manual exhauster, said means being operable by the air tension created by the operation of the manually driven exhauster, and comprising a valve co-acting with the passage leading to the power driven exhauster.

4. In a pneumatic player apparatus, an 95 action, a power driven exhauster in communication therewith, a manually driven exhauster also in communication therewith and partially through a passage in common to both exhausters, check valves between said common passage and each of said exhausters, said valves opening toward said exhausters respectively whereby the exhausting of air from said common passage by one exhauster will tend to close the check valve for the other exhauster, and means for automatically choking off the power exhauster upon the operation of the manual exhauster, said means being operable by the air tension created by the operation of the manually driven exhauster and comprising a valve co-acting with the passage leading to the power driven exhauster and between the check valve therein and the passage in common.

5. In a pneumatic player apparatus, an 115 action, a power driven exhauster in communication therewith, a manually driven exhauster, also in communication therewith, means operating to prevent the power driven exhauster from drawing air from the manually driven exhauster, and means to prevent the manually driven exhauster from drawing air from the power driven exhauster, and means to lessen the effect of the power driven exhauster on the action while said exhauster is running to thereby 125 relatively increase the effect of the manually driven exhauster when the same is operated simultaneously with the power driven exhauster.

6. In a pneumatic player apparatus, an 135

action, a power driven exhauster in communication therewith, a manually driven exhauster also in communication therewith and partially through a passage in common to both exhausters, check valves between said common passage and each of said exhausters, said valves opening toward said exhausters respectively whereby the exhausting of air from said common passage by one exhauster 10 will tend to close the check valve for the other exhauster, and pneumatically operated means to choke off the power driven exhauster when the manually driven exhauster is operated simultaneously with said power 15 driven exhauster.

7. In a pneumatic player apparatus, an action, two exhausters arranged to be operated separately or simultaneously and being in communication with said action to 20 draw air therefrom, one of said exhausters being arranged for manual operation, and automatically operable means to relatively

weaken the operation of the other exhauster on said action when the manually operable exhauster is operated simultaneously therewith. 25

8. In a pneumatic player apparatus, an action, two exhausters arranged to be operated separately or simultaneously and being in communication with said action to 30 draw air therefrom, one of said exhausters being arranged for manual operation, and means to relatively weaken the effective operation of the other exhauster on said action when the manually operable exhauster is operated simultaneously therewith, said weakening means including a pneumatic controlled by the tension of air in the manually 35 operable exhauster.
